H. R. ELLIS

SECTIONAL WINDOW SCREEN LOCK

Filed July 8, 1924

Fig. 1.

UNITED STATES PATENT OFFICE.

HORACE R. ELLIS, OF MEADVILLE, PENNSYLVANIA.

SECTIONAL-WINDOW-SCREEN LOCK.

Application filed July 8, 1924. Serial No. 724,830.

To all whom it may concern:

Be it known that I, HORACE R. ELLIS, a citizen of the United States, residing at Meadville, in the county of Crawford and State of Pennsylvania, have invented certain new and useful Improvements in Sectional-Window-Screen Locks, of which the following is a specification.

This invention relates to a sectional window screen lock and has for its object to provide a device of such class, in a manner as hereinafter set forth, with means for locking the sections of a window screen in position within the frame of a window.

Further objects of the invention are to provide, in a manner as hereinafter set forth, a sectional window screen lock, which is simple in its construction and arrangement, strong, durable, compact, thoroughly efficient and convenient in its use, readily installed with respect to the sections of the screen, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is an elevation of a sectional window screen mounted in position with respect to a sash and window frame and further showing the adaptation therewith of a locking device in accordance with this invention.

Figure 2 is a section on line 2—2, Figure 1.

Figure 3 is a fragmentary end edge view of a window screen illustrating one of the elements of the locking device secured therewith.

Figure 4 is a grouped perspective view of one of the locking bars and its anchoring member.

Figure 5 is a like view of the other locking bar and its anchoring member.

Referring to the drawings in detail, 1 denotes a window sash, 2 the window frame provided with a pair of opposed sockets 3, 4, and 8 stop members to limit the downward movement of the sash 1. A sectional win-

dow screen is indicated at 7 and the sections thereof at 5, 6. The sections of the screen are coupled together through the medium of a pair of combined guide and connecting rods 9 operating through keepers 10 and formed with stops 11. The rods 9 are secured to the inner side of the top and bottom rails of the screen section 6, as at 12, and the keepers 10 are carried by the top and bottom rails of the screen section 5. The end rail of each of the screen sections is provided with a protuberance 13, which extends into one of the sockets 3 or 4 for positioning and connecting a screen section to one side of the window frame. The foregoing elements are illustrated by way of example to show the adaptation of a locking device in accordance with this invention with respect to the sections of a sectional window screen.

The locking device, in accordance with this invention, comprises a pair of anchoring members 14, 15, a pair of locking bars, one referred to generally by the reference character 16 and the other referred to generally by the reference character 17, and a securing device for locking the bars 16 and 17 in adjusted position and which is generally referred to by the reference character 18.

The anchoring member 14 is secured to the end bar 19 of the screen section 5, and the anchoring member 15 is secured to the end bar 20 of the screen section 6. The members 14 and 15 are positioned substantially centrally with respect to the inner side of the said bars 19, 20.

The anchoring member 14, as well as the anchoring member 15 consists of a short plate 21 provided at one end with a pair of oppositely extending flanges 22, 23, each formed with an opening 24. The other end of the plate 21 is rounded, as at 25, and said plate 21, in proximity to the end 25, is formed with a polygonal-shaped socket 26.

Each of the anchoring members is secured in position through the medium of a pair of hold-fast devices 27, which extend through the flanges 22, 23 and engage in an end bar of a screen section. The heads of the hold-fast devices 27 seat in the openings 24 and said heads are then soldered over, as indicated at 27, Figure 2, to prevent removal of the hold-fast devices.

The locking bar 16 comprises a polygonal-shaped outer end portion 28 corresponding

in contour to the shape of a socket 26 and adapted to seat therein, a cylindrical intermediate portion 29 and a peripherally threaded cylindrical inner end portion 30 of materially less diameter than the portion 29. The polygonal-shaped outer portion 28, when mounted in the socket 26, prevents turning of the bar 16 when the latter is in locking position.

10 The locking bar 17 consists of a polygonal-shaped portion 30' of the same contour as a socket 26 and which is adapted to seat in said socket, and a cylindrical portion 31 of greater length than the portion 30' and 15 which is formed with a socket 32 of a length to receive the portion 30 of the bar 16. The polygonal-shaped portion 30 of the bar 17 when seated in the socket 26 prevents the turning of the bar 17 when in locking position.

20 The locking device comprises an oval-shaped nut 33, which is mounted eccentrically on the portion 30 of the bar 16 and has threaded engagement therewith. The nut 33 is adjustable lengthwise with respect to the inner portion 30 of the bar 16 and said nut is furthermore provided with an opening 34 spaced a substantial distance from that part of the nut 33 which has threaded 25 engagement with the portion 30 of the bar 16. Formed integral with the inner end of the portion 31 of the bar 17, is a small plate 35 which corresponds in shape to the shape of the nut 33, and said plate is formed with 30 a pair of spaced openings 36, 37. The opening 36 registers with the socket 32 and is provided for the passage of the portion 30 of the bar 13 into the socket 32. The opening 37 is adapted to register with the opening 34 of the nut 33 and when said openings are in registering position the hasp or shackle 38 of a lock 39 is extended through 35 said openings to lock the bars 16 and 17 to prevent the shifting of one relatively to the other.

25 When using a locking device, in accordance with this invention, the screen 7 is positioned in the frame 2 and the protuberances 13 seated in the sockets 3, 4 and which prevent the sections of the screen from being pushed out. The stops 8 prevent the sash from being lowered past the screen. The polygonal-shaped portion 28 of the bar 16 is then inserted in the socket 26 of the anchoring member 14. The locking bar 17 is then shifted on the portion 30 of the bar 16, until the polygonal-shaped portion 30' of the bar 17 is seated in the socket 26 of the member 15. The nut 33 is then revolved 30 on the threads of the portion 30 of the bar 16, until said nut is moved to abut against the plate 35 and with the opening 34 in alignment with the opening 35. The nut 33 and plate 35 are then secured together by the hasp or shackle 38 of the lock 39. The

screen is then locked securely in place. If the screen body is cut-out the locking bar remains in position to extend transversely of the window and set up a bar extending thereacross and will remain in such position until the frame sections of the screen are smashed. By the foregoing arrangement, the screen is securely locked in the window frame, due to the fact that the sections of the frame cannot be shifted towards or away from each other when the bars 16 and 17 are connected together by the lock 39.

35 It is thought that the many advantages of a locking device in accordance with this invention, for sectional window screens can be fully understood, and although the preferred embodiment of the invention is as illustrated and described, yet changes in the details of construction can be had which will fall within the scope of the invention 40 as claimed.

What I claim is:—

1. A locking device for the sections of a window screen comprising a pair of telescopic locking bars adjustable relatively to each other and each adapted to be secured to one of the sections of the screen, an adjustable nut threadedly engaging with one of said bars, extended therefrom and having its extended portion provided with an opening spaced from said bar, a fixed plate secured to and extended from the inner end of the other of said bars and having its extended portion provided with an opening for registration with the opening in said nut, and means extending through the registered openings for coupling the nut and plate together thereby maintaining the said bars in adjusted position.

2. A locking device for the sections of a window screen comprising a pair of anchoring members, each adapted to be secured to a screen section, a pair of telescopic locking bars adjustable relatively to each other and each having its outer end anchored in one of said members, an adjustable nut threadedly engaging with one of said bars, extended therefrom and having its extended portion provided with an opening spaced from said bar, a fixed plate secured to and extended from the inner end of the other of said bars and having its extended portion provided with an opening for registration with the opening in said nut, and means extending through the registering openings for coupling the nut and plate together thereby maintaining the said bars in adjusted position.

3. A locking device for a section of a window screen comprising a pair of telescopic locking bars adjustable relatively to each other and each adapted to be secured to a screen section, one of said bars provided with a lengthwise extending socket, an apertured plate secured to the inner end of said

- bar, extended therefrom and having its extended portion formed of an opening, the other of said bars formed with a reduced peripherally threaded portion extending through said plate into said socket, an adjustable nut threadedly engaging with said reduced portion and further extended therefrom and having its extended part formed with an opening adapted to register with 10 the opening in said plate, and means extending through the registered openings for connecting the nut and plate together and for maintaining the said bars in adjusted position.
- 15 4. A locking device for a section of a window screen comprising a pair of telescopic locking bars adjustable relatively to each other and each adapted to be secured to a screen section, one of said bars provided 20 with a lengthwise extending socket, an apertured plate secured to the inner end of said bar, extended therefrom and having its extended portion formed of an opening, the other of said bars formed with a reduced peripherally threaded portion extending through said plate into said socket, an adjustable nut threadedly engaging with said reduced portion and further extended therefrom and having its extended part formed with an opening adapted to register with 25 the opening in said plate, means extending through the registered openings for connecting the nut and plate together and for maintaining the said bars in adjusted position, and anchoring members having the outer ends of said bars extended therein and providing means for connecting the bars to the screen section.

In testimony whereof, I affix my signature hereto.

HORACE R. ELLIS.
